(57) **CLAIM**

The ornamental design for a clock radio with MP3 player receptacle, as shown and described.

DESCRIPTION

FIG. 1 is a top, front, right side perspective view of a clock radio with MP3 player receptacle showing my new design; FIG. 2 is a side view thereof, the opposite side being a mirror image;

FIG. 3 is a top view thereof;

FIG. 4 is a front view thereof;

FIG. 5 is a rear view thereof;

FIG. 6 is a bottom view thereof; and,

FIG. 7 is a perspective view with environmental material.

The broken line showing of an MP3 player is for illustrative purposes only and forms no part of the claimed design.
